(57) **CLAIM**

The ornamental design for an electric drive unit, as shown and described.

DESCRIPTION

FIG. 1 is a bottom view of an electric drive unit according to the present disclosure.

FIG. 2 is a top view of the electric drive unit of FIG. 1.

FIG. 3 is a front view of the electric drive unit of FIG. 1.

FIG. 4 is a right view of the electric drive unit of FIG. 1.

FIG. 5 is a back view of the electric drive unit of FIG. 1.

FIG. 6 is a left view of the electric drive unit of FIG. 1.

FIG. 7 is a front perspective view of the electric drive unit of FIG. 1; and,

FIG. 8 is a rear perspective view of the electric drive unit of FIG. 1.
